JAMES S. PATTEN, OF BALTIMORE, MARYLAND.

SOUNDING TOY.

SPECIFICATION forming part of Letters Patent No. 723,909, dated March 31, 1903.

Application filed February 5, 1901. Serial No. 46,112. (No model.)

To all whom it may concern:

Be it known that I, JAMES S. PATTEN, residing at Baltimore, in the State of Maryland, have made certain new and useful Improvements in Sounding Toys, of which the following is a specification.

My invention is an improvement in sounding toys, and particularly in that class of devices in which a cap in a suitable holder is carried on the end of a cane-like staff and is exploded by striking it against the pavement; and the invention consists in certain novel constructions and combinations of parts, as will be hereinafter described and claimed.

In the drawings, Figure 1 is a side view of my toy ready for use. Fig. 2 is a detail side view illustrating the manner of producing the cane or staff from a wire rod. Fig. 3 is a detail side view of the lower portion of the device. Fig. 4 is a longitudinal section on about line 4-4 of Fig. 5, the cane being in place. Fig. 5 is a bottom plan view of the head of the toy. Fig. 6 is a sectional view on about the same line as Fig. 4, the tip of the cane being bent to secure it to the head and the cap being partly inserted. Fig. 7 is a detail section on about line 7-7 of Fig. 4, and Figs. 8 and 9 are respectively a longitudinal section and a bottom plan view illustrating a head with more than two legs.

The complete toy, as shown, includes the cane A and the head B at the lower end thereof. I prefer to make the head A of a suitable wire whose end is tapered, as shown in Fig. 4, and to secure this tapering end by taking wire in lengths equal to twice the length of the cane and cutting them at the middle diagonally, as shown at C in Fig. 2, the ends of the wire being cut squarely, as shown at C'. By this means I secure the cane length with its end tapered at A', as best shown in Fig. 4, thus providing the end of the cane with a portion which may conform to and fit tightly in a tapered opening in the toy-head and is reduced at its extremity so it can be conveniently bent, as shown at A² in Fig. 6, to secure the cane tightly to the head.

The head B may be formed of suitable metal and comprises the body B' and legs D at the lower end thereof. In constructing the head it is preferably tapered, converging toward its lower end, and is slotted from such

end at E, producing the legs D, whose opposite edges D' are spaced apart, forming a plurality of slots or openings E, which lead to the periphery of the head at different points in its circumference. This is important not only in the construction of the device, but also in its operation, as it affords a vent for the explosion of the cap in different directions in the operation of the device and also renders practicable the production of the head by casting ready for use. This result, it will be seen, is secured by the provision of the plurality of slots or openings E, leading from the space F, inclosed within the leg, so I can employ a number of core connections for uniting the core employed in producing the central opening F with the body of sand around the head. If only one lateral opening E were provided, it would be practically impossible to cast the device, as the single core connection would be broken down by the flow of metal, not being reinforced on the opposite side of the central core, and the casting operation could not be carried out in a practical way. It should be noticed that the central opening F, which receives the cap G, is tapered, converging toward its upper end, and forms a tapered recess in which is introduced the cylindrical body of the cap G, the rim of the cap bearing beneath the legs D, as will be understood from Figs. 3 and 6.

In the body B', I form a downwardly-tapering opening b', which is in line with and communicates with the opening F in the lower portion of the head B, as will be understood from Figs. 4, 6, and 7. The tapered end of the cane A is inserted in the opening b' and fits therein with its reduced lower end protruding below the body B' and bent beneath said body in the upper end of one of the slots E, as shown in Fig. 6, thus securing the head firmly to the cane A.

It will be noticed that the slots E flare toward their lower ends and also flare from their inner toward their outer edges, and it will also be noticed that the opening F leads squarely upward, so that the force of the explosion of the cap is directed in line with the cap, so it will operate in reacting to loosen the cap in the opening F and eject the cap. This is facilitated by the tapering form of the space F, in which the cap is seated, as when

the cap is forced home in the tapered seat and then is released to even the slightest extent its hold within the space F is lost, and it will drop out or can be withdrawn without any difficulty.

In securing the operation of the explosion to eject the cap I prefer to form the top of the space F in the complete toy concave or dished, so the explosion will react with great force 10 against the cap and eject the same as desired. In the construction shown the bottom of the body B' is dished at the center, and one of the slots E extends farther up than the others and receives the bent end of the cane, as 15 shown in Figs. 4 and 6.

It will be noticed that the lower outer edge of the head is slightly rounded or chamfered at H, while the lower end of the head at h is made flat to form a proper bearing for the 20 flange of the cap.

In Figs. 1 and 3 to 7, inclusive, the head is shown as provided at its lower end with two depending legs. It will be understood that 25 the number may be increased without departing from the broad features of my invention, and in Figs. 8 and 9 I show a head provided with three depending legs.

It may be said that in the operation of the device, the vertical bore being downwardly- 30 tapering, the explosion of the cartridge may tend to loosen the cartridge in the bore and that the explosion may also result in the rending or tearing open of the cartridge-shell, driving the ragged edges of the shell into the 35 side slot, and that by making said slot downwardly tapering the shell may be easily removed from the bore notwithstanding the action of the explosion; also, that the flaring edges of the side slot may be useful in giving 40 free vent to the gases of the explosion, as well as serving to facilitate the introduction of an

instrument for removing the shell from the side slot or central bore.

Having thus described my invention, what I claim, and desire to secure by Letters Patent, is—

1. The improved toy herein described comprising the head having the upper body portion provided centrally with a downwardly-converging opening and provided on the under side of said head with a plurality of legs spaced apart at their adjacent edges, and also spaced apart at their inner sides by the central upwardly-converging opening in line with the downwardly-converging opening in the 55 body portion and communicating therewith and also in communication with the spaces between the legs, and the cane or handle having its lower end tapered to fit the central opening in the body portion and of a length 60 to extend below said body portion and bent beneath the same into one of the spaces between the depending legs substantially as and for the purposes set forth.

2. A toy having a head provided at its lower 65 end with a seat for the cap and having in its upper or body portion a downwardly-converging opening, and the cane tapered at its lower end and inserted at such end in said opening and bent at its lower end below the body portion 70 of the head, substantially as set forth.

3. A toy having a head provided at its lower end with means for receiving and exploding a cap and a wire handle bent at its lower end into connection with the upper end of said 75 head substantially as set forth.

JAMES S. PATTEN.
